(57) **CLAIM**

The ornamental design for a mailing tube with rectangular exterior, as shown and described.

DESCRIPTION

FIG. 1 is a front perspective view of a mailing tube with rectangular exterior showing my new design;

FIG. 2 is a front elevation view thereof;

FIG. 3 is a top plan view thereof, the left side elevation view,

the right side elevation view, and the bottom plan view being

identical images thereof; and,

FIG. 4 is a cross-sectional view thereof, taken along line 4-4 of FIG. 2.

The broken lines shown in FIG. 4 depict portions of the mailing tube with rectangular exterior that form no part of the claimed design.

1 Claim, 2 Drawing Sheets
